UNITED STATES PATENT OFFICE

HOWARD MARSTON, OF CLAREMONT, NEW HAMPSHIRE, ASSIGNOR TO SULLIVAN MACHINERY COMPANY, A CORPORATION OF MASSACHUSETTS

ATTACHMENT FOR PERCUSSIVE TOOLS

Application filed December 31, 1923. Serial No. 683,618.

This invention relates to percussive cutting mechanisms.

It has for its object to provide an improved means for breaking concrete, cutting asphalt, or operating upon other similar materials. It is well known that when a street has been paved and it becomes necessary to tear up the same, for instance, to lay new pipes or repair old ones, it is necessary to cut the pavement by any of several well known methods. One method which has proven very successful is to use a percussive motor and tool having either a bull point or chisel edge, the latter type of tool being well adapted to cut through the asphalt and into the concrete. It is well known that in the latter operation when the steel has been driven to the required depth the same must be laterally moved in order to allow removal of the steel to start a new cut or to raise the material being cut.

In my improved device I provide means whereby, if desired, it is not necessary to remove the tool or stop operation of the motor, thus allowing the same to cut continuously along a predetermined line, or on the other hand, if the steel is to be removed or the material pried up, my improved means will facilitate such an operation. To accomplish this my invention has for another object to provide improved means which will allow a prying action with a fulcrum substantially adjacent the working end of the steel, thus allowing a great leverage. Another object is to provide improved means using a percussive type of drilling mechanism. A further object is to provide improved means whereby the depth of the cutting steel will be limited and whereby the same may be readily moved to assist in prying the material that has been cut. Another object is to provide improved means detachably mounted on a steel. Another object is to provide improved means whereby a tool retainer may be used in combination therewith. A still further object is to provide improved means for limiting movement of my prying member relative to the steel during operation. A further object is to provide improved means for limiting

said movement with the aid of the motor casing.

In the accompanying drawings I have shown for purposes of illustration one form which my invention may assume in practice. 55

In these drawings,—

Fig. 1 is a front elevation showing the tool disposed in material being cut or broken.

Fig. 2 is a side elevation partly in section to show details of construction and also showing the tool in a position similar to that shown in Fig. 1. 60

Fig. 3 is a transverse sectional detail on line 3—3 of Figs. 1 and 2.

I have shown my improved device associated with a usual percussive type motor 1 having large transverse handles 2 with a usual actuating fluid controlling valve 3 disposed adjacent the same. Mounted upon the lower end of the motor is a usual tool supporting mechanism 5 adapted to receive a steel 6, herein shown as of a hexagonal shaped cross section and having suitable lug means, herein in the form of a collar 7, adapted to limit its inward movement and also to engage a 75 tool retainer 8 on its forward movement. The retainer 8 is of standard construction and is adapted to be swung out of alignment with the collar 7 as by a pivotal connection 9 carried on the lower end of the member 5. 80

It is to be understood that my improved device can be used wherever it is desired to break or cut material in any manner that would require a prying action. To accomplish this prying action I provide a fulcrum member 10 having a longitudinal groove 11 within which the steel 6 is disposed and detachably held thereto by clips 12 surrounding the same. The upper end of the member 10 is adapted to abut against the lower end of the motor 1 and thereby be positively limited in its upward movement although it will be understood that any other suitable means might be used to accomplish this limiting action. Suitable recesses 14 and 15 in the upper side of the member 10 receive the collar 7 and retainer 8. In order to perform the prying action I have shown an enlarged rounded portion 16 disposed on the lower end of the member 10 and adapted to engage the 100

surface of the material being broken or cut and is also of such width that it will bridge a gap formed by a steel having a chisel-like point 17 which is particularly adapted for 5 continuous operation.

In the operation of my device the operator will force the steel with the aid of the drilling motor into the material to be broken or cut and when the same has penetrated to a depth 10 so that the portion 16 will engage the surface of the material, the operator pushes the handle down in a direction indicated by the arrow A in Fig. 2 and thus forces the point 17 of the steel upwardly which tends to lift 15 the material and free the steel to allow the operation to be repeated. During this operation the motor is continuously run and the steel not withdrawn from the material, the prying action being allowed during continuous 20 operation for the portion 16 follows the cut and is wide enough to bridge the gap formed by the tool 17. Thus such an operation would be something like a "can opening action." During the prying action the 25 member 10 will tend to be forced upwardly, but such action is prevented by allowing the upper end of the member to come in contact with the end of the motor. It will of course be obvious that if a substantially smooth surface 30 is desired along a predetermined line as B in Fig. 2, the operator would make many short prying movements and also that the motor need not operate during prying, the whole mechanism thus, in effect, being capable 35 of use as a crow bar with an attached fulcrum.

It will thus be seen that I have provided an extremely simple means whereby the motor can be continually operated and the point 40 17 thus continuously fed along a predetermined line, thereby making a substantially clean surface cut and one having a definite depth, which depth is controlled without any exertion on the part of the operator. When 45 it is desired to change steels, it is only necessary to swing the tool retainer 8 out of alignment with the collar 7, remove the clips 12 which allows the member 10 to be removed, an operation requiring only a small interval 50 of time.

While I have in this application specifically described one form which my invention may assume in practice, it will be understood that this form of the same is shown for 55 purposes of illustration and that the invention may be modified and embodied in other forms without departing from its spirit or the scope of the appended claims.

What I claim as new and desire to secure by 60 Letters Patent is:

1. The combination with a percussive motor, a cutting tool actuated thereby and having a lug formed thereon, and a tool retainer cooperating with said lug, of means for 65 fulcruming said tool directly on the material

to be cut, said means having portions engaging with said lug and retainer.

2. The combination with a percussive motor, a cutting tool actuated thereby and having a lug formed thereon, and a tool retainer 70 cooperating with said lug, of means for fulcruming said tool directly on the material to be cut, said means having portions adapted to receive said lug and retainer and abutting against the body of said motor. 75

3. An attachment for a percussive tool having a steel retainer, comprising a fulcrum member about which the tool is adapted to be swung, and means for attaching said fulcrum member to the tool comprising a plurality of spaced supporting clips carried by said member and adapted to surround the steel of the tool and a notch in said fulcrum member adapted to receive a portion of the tool retainer. 80

4. An attachment for a percussive tool having a collared steel, comprising a fulcrum member about which the tool is adapted to be swung, and means for attaching said fulcrum member to the tool comprising a plurality of spaced clips carried by said member and adapted to surround the steel of the tool, and a notch in said fulcrum member adapted to receive the collar on the steel. 85

5. An attachment for a percussive tool having a collared steel and a tool retainer cooperating therewith, comprising a fulcrum member having means abutting against the body of the tool about which the latter is adapted to be swung, and means for attaching 90 said fulcrum member to the tool comprising a plurality of clips carried by said member and adapted to surround the steel and notches in said fulcrum member adapted to receive the collar on the steel and a portion of the 100 tool retainer. 105

6. The combination with a percussive motor, and a cutting tool actuated thereby having a cutting edge, of means projecting laterally from the tool for providing a bearing for 110 said tool on the material being cut along a line substantially perpendicular to the cutting edge, whereby the tool may be pivotally moved about an axis extending transversely with respect to said edge and in a plane parallel 115 to a line parallel to said cutting edge.

7. The combination with a percussive motor and a cutting tool actuated thereby and having a straight cutting edge adapted to cut continuously along a predetermined line, of 120 fulcruming means supported on the side of the tool in alinement with the cutting edge thereof, said fulcruming means adapted to engage directly on the surface of the material being cut along a line substantially perpendicular to the cutting edge to allow said tool to pry material in front thereof and in substantial alinement with said cutting edge. 125

8. In combination with a percussive motor, a cutting tool actuated thereby having a cut- 130

- ting edge, and means for providing, at a point in advance of the forward end of said motor, a fulcrum for said tool on the material being cut for pivoting the tool about an axis substantially perpendicular to a plane passing through the longitudinal center line of the tool and including said cutting edge, said fulcrum means being adapted to engage the material being cut along a line substantially perpendicular to said cutting edge.
- 10 9. The combination with a percussive motor, and a cutting tool actuated thereby and having a straight cutting edge adapted to cut continuously along a predetermined line, of a fulcrum member, means for detachably mounting said member on said cutting tool, said member abutting against the motor, and said cutting tool being movable longitudinally relative to said member.
- 15 10. The combination with a percussive motor, and a cutting tool actuated thereby and having a straight cutting edge adapted to cut continuously along a predetermined line, of means providing a fulcrum for said tool about an axis extending transversely of said line, said fulcrum member being loosely mounted on said cutting tool and abutting against said motor, whereby said tool is adapted to be pivoted about said fulcrum 25 during a cutting operation.
- 30 In testimony whereof I affix my signature.
HOWARD MARSTON.
